TELEVISION RECEIVER

Hiroshi Saito, Osaka, Kitaro Kimura, Saita, and Iwao Nakajima, Osaka, Japan, assignors to Matsushita Electric Industrial Co., Ltd., Osaka, Japan

Filed Oct. 22, 1971, Ser. No. 191,954

Claims priority, application Japan Apr. 22, 1971

Term of patent 14 years

Int. Cl. D14—03

U.S. Cl. D56—4 D

FIG. 1

FIG. 2

FIG. 3

FIG. 4

FIG. 5

FIG. 1 is a left side, top and front perspective view of a television receiver, showing our new design with the handle in retracted position;

FIG. 2 is a top plan view;

FIG. 3 is a front elevational view with the handle in extended position;

FIG. 4 is a right side elevational view with the handle in extended position; and

FIG. 5 is a rear, bottom and left side perspective view thereof.

We claim:

The ornamental design for a television receiver, as shown and described.
